US0D1111127S

(12) **United States Design Patent** (10) **Patent No.:** **US D1,111,127 S**
(45) **Date of Patent:** **** Feb. 3, 2026**

(54) **BASE FOR A STORMWATER DETENTION AND RETENTION SYSTEM**

(71) Applicant: **SPEL Environmental Pty Ltd, Hornsby (AU)**

(72) Inventors: **Andy Hornbuckle, Sydney (AU); James Hales, Sydney (AU)**

(**) Term: **15 Years**

(21) Appl. No.: **29/929,743**

(22) Filed: **Feb. 23, 2024**

(30) **Foreign Application Priority Data**

Aug. 25, 2023 (AU) 202315550

(51) **LOC (15) Cl.** **23-01**

(52) **U.S. Cl.**

USPC **D23/202**

(58) **Field of Classification Search**

(57) **CLAIM**

The ornamental design for a base for a stormwater detention and retention system, as shown and described.

DESCRIPTION

FIG. 1 is a top perspective view of a base for a stormwater detention and retention system showing the new design;

FIG. 2 is a top view thereof;

FIG. 3 is a bottom view thereof;

FIG. 4 is a front view thereof;

FIG. 5 is a rear view thereof;

FIG. 6 is a left side view thereof; and,

FIG. 7 is a right side view thereof.

1 Claim, 7 Drawing Sheets
